UNITED STATES PATENT OFFICE.

CHARLES H. PATTERSON, OF TRINIDAD, COLORADO.

COLT AND CALF WEEANER.

974,421.

Specification of Letters Patent.

Patented Nov. 1, 1910.

Application filed July 5, 1910. Serial No. 570,287.

To all whom it may concern:

Be it known that I, CHARLES H. PATTERSON, citizen of the United States, residing at Trinidad, in the county of Las Animas and State of Colorado, have invented new and useful Improvements in Colt and Calf Weaners, of which the following is a specification.

My present invention pertains to colt and calf weaners of the muzzle type; and it consists in the peculiar and advantageous weaner hereinafter described and definitely claimed.

In the drawings accompanying and forming part of this specification: Figure 1 is a view illustrating the application of the weaner to a colt and also illustrating the manner in which the sections are separated when the colt puts its head down to eat or graze. Fig. 2 is an enlarged perspective view showing the sections of the weaner closed against each other. Fig. 3 is a detail vertical section illustrative of the manner in which the hooks on the upper section operate to lock the forward end of said section to the forward end of the lower section when the colt puts its head up to nurse.

Similar letters designate corresponding parts in all of the views of the drawings, referring to which:

A is the lower section of my novel weaner. The said section comprises a bail-shaped main frame *a* and comparatively small wires *b* connected to the side bars and front bar of the main frame and forming in combination therewith a basket. Connected to the rear portions of the side bars of the main frame *a* is an arch bar *c* which is designed to rest over the animal's nose with a view of holding the section A close against the under side of said muzzle. It will also be noted by reference to Figs. 1 and 2 that the side bars of the main frame *a* terminate at their rear ends in angularly disposed arms *d* which are provided with intermediate lateral deflections *e* and terminate, in turn, in eyes *f*. The lateral deflections *e* of the arms *d* are for the connection of the cheek straps *g* of a halter, which may be and preferably is of the construction shown in Fig. 1.

B is the upper section of the weaner, and C C are the hooks on the forward end of the said upper section; the said hooks being, by preference, of flat material. The upper section B comprises a bail-shaped main frame *h* having angularly disposed arms *i* which

are pivotally or loosely connected at *j* to the eyes *f* of section A, an arched bar *k* connected to the upper portions of the angularly disposed arms *i*, and comparatively small wires *l* connected to the frame *h* and the arched bar *k* and serving in connection therewith to form an upper basket. The hooks C are pivotally or loosely connected at *m* to the forward bar of the main frame *h* comprised in the upper section B, and are preferably shaped as best illustrated in Figs. 2 and 3.

It will be understood from the foregoing that when the colt puts its head down to eat, the upper or forward section B stays up and affords an opening between its forward end and the forward end of the lower or rear section A sufficiently wide to enable the colt to freely eat or drink. The colt equipped with the weaner can also eat long or short grass or hay on a stack, but when the colt puts its nose up as is necessary to enable it to nurse, the upper or forward section B drops down on the rear or lower section, and then the hooks C gravitate or swing into engagement with the forward end of the frame *a* in section A, and thereby prevent the colt from rubbing or moving one of the sections away from the other. In other words, when the colt tips its nose up, the hooks C securely lock the forward end of the section B to the corresponding end of the section A, and hence the colt is effectually prevented from nursing. When, however, the colt puts its head down, the hooks C swing away from and out of engagement with the forward end of the section A, and then the forward ends of the sections are adapted to separate for the purpose before stated.

While I have shown and described one form of my invention, it is to be understood that I am not limited to the details or the form or relative arrangement of parts disclosed, but that modifications may be made therein without departing from the spirit thereof.

Having described my invention, what I claim and desire to secure by Letters Patent, is:

1. In a colt and calf weaner of the muzzle type, the combination of a lower or rear section comprising a bail-shaped main frame having angularly-disposed rear arms provided with intermediate deflections, an arch-bar connected at its ends to the main frame, and wires connected to the main frame and

- forming therewith a basket; an upper or forward section comprising a bail-shaped main frame having angularly-disposed rear arms pivotally connected to the arms of the 5 first-named section, an arch-bar connected at its ends to the main frame and wires connected to the main frame and arch-bar and forming therewith a basket, and hooks pivoted to the forward end of the main frame 10 of the second-named section and adapted to swing into and out of engagement with the forward end of the main frame of the first-named section, for the purpose set forth.
2. In a colt and calf weaner of the muzzle 15 type, the combination of a lower or rear section having a basket and a transverse-arch-bar adapted to rest over an animal's nose and also having upwardly-directed rear arms, and an upper or forward section having a basket and also having upwardly-directed rear arms connected with and adapted to swing on the arms of the first-named section.
3. In a colt and calf weaner of the muzzle 20 type, the combination of a lower or rear section having a basket and a transverse-arch-bar adapted to rest over an animal's nose and also having upwardly-directed rear arms, an upper or forward section having a basket and also having upwardly-directed rear arms connected with and adapted to

swing on the arms of the first-named section, and gravitating means on the second-named section for engaging the first-named section on upward inclination of the animal's muzzle and for moving out of engagement with said section on downward inclination of the animal's muzzle. 35

4. In a colt and calf weaner of the muzzle type, the combination of sections pivotally 40 connected one to the other and adapted to receive the animal's muzzle between them, and hooks pivoted to the forward end of one section and adapted, when the animal tips its muzzle upward, to swing into engagement with the forward end of the other section. 45

5. In a colt and calf weaner of the muzzle type, the combination of sections pivotally 50 connected one to the other and adapted to receive the animal's muzzle between them, and gravitating means on one section for engaging the other section and locking the sections together when the animal tips its muzzle upward. 55

In testimony whereof I have hereunto set my hand in presence of two subscribing witnesses.

CHARLES H. PATTERSON.
